DESIGN FOR A LAMP SOCKET

Clarence Birdseye and Harold Douglas Wilson,
Gloucester, and Walter N. Heath, Rockport,
Mass., assignors to Birdseye Electric Corpora-
tion, Dover, Del., a corporation of Delaware

Application January 24, 1938, Serial No. 74,504

Term of patent 14 years

To whom it may concern:

Be it known that we, Clarence Birdseye, H. Douglas Wilson and Walter N. Heath, all citizens of the United States, and residents of Gloucester, Gloucester, and Rockport, respectively, in the county of Essex and Commonwealth of Massachusetts, have invented a new, original, and ornamental Design for a Lamp Socket, of which the following is a specification, reference being had to the accompanying drawing, forming a part thereof, in which the figure is a view in elevation of a lamp socket showing our invention.

The dominant feature of our design resides in a series of parallel circular ribs with rounded external edges separated by deep parallel wall grooves and constituting collectively the intermediate portion of the socket.

We claim:

The ornamental design for a lamp socket, substantially as shown and described.

CLARENCE BIRDSEYE.
